UNITED STATES PATENT OFFICE.

RICHARD S. GIESE, OF SEWICKLEY HEIGHTS TOWNSHIP, ALLEGHENY COUNTY,
PENNSYLVANIA.

DESIGN FOR A GLASS TUMBLER.

Application filed December 17, 1927. Serial No. 24,513. Term of patent 7 years.

To all whom it may concern:

Be it known that I, RICHARD S. GIESE, a citizen of the United States, residing in Sewickley Heights Township, in the county of Allegheny and State of Pennsylvania, have invented a new, original, and ornamental Design for Glass Tumblers, of which the following is a specification, reference being had to the accompanying drawing, forming part thereof.

In the accompanying drawings Fig. 1 is a view in perspective and Fig. 2 is a view in

horizontal section of a glass tumbler showing my new design.

In the drawing the contour of the inner surface of the tumbler, seen through the transparent walls, is conventionally indicated in dotted lines. The shaded upper rim and the narrow band beneath are opaque.

I claim:

The ornamental design for a glass tumbler, as shown and described.

RICHARD S. GIESE.
